BY HIS ATTORNEY *Benj P. Schmitt*

UNITED STATES PATENT OFFICE.

HERMAN KOESTER, OF WATERBURY, CONNECTICUT, ASSIGNOR TO THE BRISTOL COMPANY, OF WATERBURY, CONNECTICUT, A CORPORATION OF CONNECTICUT.

ELECTRICAL LOUD-SPEAKING RECEIVER.

Application filed September 23, 1922. Serial No. 589,979.

To all whom it may concern:

Be it known that I, HERMAN KOESTER, a citizen of the United States, and a resident of Waterbury, in the county of New Haven 5 and State of Connecticut, have invented certain new and useful Improvements in Electrical Loud Speaking Receivers, of which the following is a specification.

The invention relates to electrical receiver 10 apparatus for amplifying sounds, such receiver devices being generally termed "Loud speaking receivers". The invention relates more particularly to that type of loud speaking receivers in which there is employed a permanent magnet of such proportions as to carry all the operative parts, and in which a one-piece armature lever is 15 provided for actuating the diaphragm, the said lever being suitably fulcrumed to the 20 magnet.

It has for its object to provide a positively located and a more or less balanced armature for this purpose, and in which the magnetic attraction thereon will not cause an undue 25 tension on the diaphragm. A further object of the invention consists in providing an armature mounting of a minimum number of parts and so arranged as to eliminate friction and the usual adjusting spring. 30 The novel mounting, moreover, is of such proportions as to suit the desired tension, and will serve to positively locate the lever with reference to the pole piece of the magnet. As a result of the improved construction, the diaphragm will be caused to 35 respond more readily and be more sensitive to the fluctuation of current thru vibration imparted thereby to the lever.

The nature of the invention, however, will 40 best be understood when described in connection with the accompanying drawings, in which—

Fig. 1 is a longitudinal section thru the receiver device.

Fig. 2 is a horizontal section taken on the line 2—2, Fig. 1, looking in the direction of the arrows.

Fig. 3 is a transverse section taken on the line 3—3, Fig. 1, looking in the direction of the arrows and with a portion broken away.

Similar characters of reference designate corresponding parts thruout the several views.

Referring to the drawings, 10 designates 55 a suitable casing or container wherein the entire apparatus may conveniently be mounted and housed. The device itself comprises a permanent U-shape magnet 11 of substantial proportions and designed to 60 carry the entire apparatus, one leg of said magnet being shorter than the other, the legs having pole pieces 12 and 13 respectively and directed at right angles from the 65 ends thereof. The pole piece 13, furthermore, is provided with a solenoid 14 thru which current passes as received from a transmitting apparatus (not shown), and as is well understood. Suitable leads 15 are 70 connected to the said solenoid for this purpose.

The magnet 11, in addition, carries a sound box 16 which is adjustably secured thereto for slight angular motion to assist in the tensioning of a lever, hereinafter 75 more fully described, the adjustment being effected, for example, thru nuts 17 working on a screw 18. A nut 19, furthermore, serves to secure the sound box and attached magnet to the casing 10; and an outlet 20 80 extends therefrom thru the said casing and may receive a suitable horn 21 or other amplifying member.

In order to effect the amplification, the diaphragm 22 of the sound box is to be 85 vibrated in accordance with the fluctuations of current received from the transmitting circuit 15, the diaphragm being held securely in the sound box 16 by rubber washers 23 or the like, in the usual manner. These 90 fluctuations affect the magnetic attraction of the pole piece 13 for the armature end of a one-piece lever 24 whose other end is associated with the diaphragm 22, and is caused to bear thereon under a predetermined tension in accordance with the normal 95 attraction of the pole piece 13 for its corresponding end. The diaphragm end of the lever 24 may be fixedly attached to the diaphragm 22; but it is preferred to provide a loose connection between said diaphragm and lever end, as indicated, and as is more 100 particularly set forth in my co-pending application Serial No. 569,332.

To afford a suitable mounting for the 105 armature lever 24 and which at the same time will provide a force more or less opposing the magnetic attraction of the pole

piece 13 for the lever armature and thus more or less substantially balance the lever, the latter is designed to be secured to the pole piece 12 by a resilient member such as 5 a flat strip or piece 25 of spring-metal. To this end, the strip 25 is arranged to be fastened, as by screws 26, to the upright portion or side of the pole piece 12 and its bifurcated end brought over the lever and secured 10 thereto as by screws 27, in manner such that the armature lever, preferably, does not quite touch the top of the pole piece 12; and, of course, to be slightly above the top of the pole piece 13. The strip 25 is of such 15 resiliency and is so adjusted that the desired air gap will be maintained between the armature lever and pole piece 13 without producing an undue stress on the diaphragm 22, which is thus in a more or less neutral 20 condition and will most readily respond to the vibrations imparted thereto by the armature lever. An adjustment of the air gap is possible thru the screw 18, as hereinbefore set forth. In the use of the aforesaid resili- 25 ent mounting of the armature lever, furthermore, the usual type of bearing as well as an adjustable tensioning spring are eliminated and the armature lever is positively located with reference to the pole pieces.

30 I claim:-

1. An electrical loud speaking receiver, comprising a permanent magnet having two pole pieces, a diaphragm, an armature lever engaging at one end with the diaphragm, its 35 other end being under the influence of one of the said pole pieces, a solenoid about the latter pole piece, and a resilient member securing the armature lever to the other of the said pole pieces.
- 40 2. An electrical loud speaking receiver, comprising a permanent magnet having two pole pieces, a diaphragm carried by the magnet, an armature lever engaging at one end with the diaphragm, its other end being 45 under the influence of one of the said pole pieces, a solenoid about the latter pole piece, and a resilient member securing the arma-

ture lever to the other of the said pole pieces.

3. An electrical loud speaking receiver, 50 comprising a permanent magnet having two pole pieces, a diaphragm, an armature lever engaging at one end with the diaphragm, its other end being under the influence of one of the said pole pieces, a solenoid about 55 the latter pole piece, and a flat spring-metal strip attached to the other of the said pole pieces and to the armature lever.

4. An electrical loud speaking receiver, 60 comprising a permanent magnet having two pole pieces, a diaphragm, an armature lever engaging at one end with the diaphragm, its other end being under the influence of one 65 of the said pole pieces, a solenoid about the latter pole piece, a resilient member securing 70 the lever to the other of the said pole pieces, and means to adjust the diaphragm relatively to the armature lever.

5. An electrical loud speaking receiver, 70 comprising a permanent magnet having two pole pieces, a diaphragm carried by the magnet, an armature lever engaging at one end with the diaphragm, its other end being under the influence of one of the said pole pieces, a solenoid about the latter pole piece, 75 a flat spring-metal strip attached to the other of the said pole pieces and to the armature lever, and means to adjust the diaphragm relatively to the lever.

6. An electrical loud speaking receiver, 80 comprising a permanent magnet having two pole pieces, a diaphragm, an armature lever engaging at one end with the diaphragm, its other end being under the influence of one 85 of the said pole pieces, a solenoid about the latter pole piece, and a flat spring-metal strip attached to the side of the other of 90 said pole pieces, brought over the said armature lever and attached thereto.

Signed at Waterbury, in the county of 90
New Haven and State of Connecticut, this
21st day of September, A. D. 1922.

HERMAN KOESTER.
